(57) **CLAIM**

The ornamental design for a combination of brackets with lumber or engineered wood product for metal stud walls, as shown and described.

DESCRIPTION

FIG. 1 is a front perspective view of the first embodiment of a combination of brackets with lumber or engineered wood product for metal stud walls, showing my new design; FIG. 2 is an enlarged-scale front perspective view of FIG. 1, with portions of environment broken away;

FIG. 3 is a front perspective view comparable to FIG. 2 except with all environment removed from view;

FIG. 4 is front elevational view of FIG. 3;

FIG. 5 is a top plan view thereof;

FIG. 6 is a bottom plan view thereof;

FIG. 7 is a right side elevational view thereof, the opposite side a mirror image thereof;

FIG. 8 is a section view taken along line VIII-VIII in FIG. 4;

FIG. 9 is a rear elevational view thereof;

FIG. 10 is a front perspective view of the second embodiment of a combination of brackets with lumber or engineered wood product for metal stud walls, showing my new design;

FIG. 11 is a front perspective view comparable to FIG. 10 except with all environment removed from view;

FIG. 12 is front elevational view of FIG. 11;

FIG. 13 is a top plan view thereof;

FIG. 14 is a bottom plan view thereof;

FIG. 15 is a right side elevational view thereof, the opposite side a mirror image thereof;

FIG. 16 is a section view taken along line XVI-XVI in FIG. 12; and,

FIG. 17 is a rear elevational view thereof.

The dot dot dash lines immediately adjacent to the shaded areas represent bounds of the claimed design. All other
